UNITED STATES PATENT OFFICE.

EDWARD J. WILLIAMS, OF RIVER EDGE, NEW JERSEY.

METHOD AND MEANS FOR LAYING SHINGLES.

Application filed January 11, 1922. Serial No. 528,557.

To all whom it may concern:

Be it known that I, EDWARD J. WILLIAMS, a citizen of the United States, and a resident of River Edge, State of New Jersey, have invented a certain Improvement in Methods and Means for Laying Shingles, of which the following is a specification.

In laying shingles upon a roof much labor and cost and loss of time are involved in the accurate alignment and correctly measured spacing of the shingles.

The present invention relates to a method and means whereby this alignment and spacing may be rapidly, accurately and cheaply accomplished under factory conditions, and whereby the roofer may be supplied with packages of shingles which have only to be unfolded and laid down to be ready for nailing in place.

20 In order to accomplish this the invention consists in securing the shingles to flexible strips in proper alignment and properly spaced, so that the assembled group so formed may be folded in convenient packages for shipment. In its more specific preferred embodiment, the securing strips used are made of thin soft metal adapted to be folded down upon the edges of the shingles.

30 Certain embodiments of the invention are illustrated in the accompanying drawings wherein Figure 1 is a face view of one end of a preferred securing strip, Figure 2 is a similar view of one end of the same with two shingles in place. Figure 3 is an end view of a part of a bundle ready for shipment, Figure 4 is a sectional view through an assembled group, and Figure 5 is a face view of a modified form.

40 The securing strip for the preferred form of the invention, as shown in Figure 1, consists of a band of thin soft metal, preferably mild steel, shown at 10, which is cut or stamped to form folding flaps 11 along one 45 longitudinal edge and at the two ends. These flaps are spaced in accordance with the proper side by side spacing of the shingles, allowing the usual distance between the contiguous edges of the same. Pairs of 50 openings 12 are also punched in the sheet, the material from which is left standing at right angles to the strip to form lugs as shown at 13. These are so spaced that the left hand lug of each pair and the right

hand lug of the next are parted by the 55 width of a shingle. As shown, these lugs are placed to correspond with the folding flaps 11. At the end of each band 10, the flap 11 is used to confine the outer edge of shingles, in place of a lug 13. 60

The shingles 14 are then laid side by side between the lugs 13, as shown in Figure 2, and are secured in place by bending the flaps 11 and the lugs 13 over the top and side edges of each shingle as shown (see Figures 65 2 and 4). The dotted lines in Figure 1 show the space provided to accommodate the thickness of the shingles.

When the shingles have been thus secured in an aligned and spaced group (usually 70 thirteen in a group) the strip is bent back and forth in an accordion pleat as shown in Figure 3. This provides a convenient, compact and secure bundle for shipment. If desired, the strip can be weakened between the shingles by cutting out an opening 12^a and thereby making it easier to bend the strip in the manner just described. 75

In use, the roofer has only to stretch out one of these bundles to form at once a 80 properly aligned and spaced assembly of shingles which can be laid along the roof and quickly secured in place by nailing.

The invention covers any mode of forming 85 aligned and spaced groups of shingles connected by one or more flexible strips of any appropriate material.

For instance, as shown in Figure 5, the narrow bands 15, simply riveted to the backs of the shingles may take the place of 90 the band 10.

What is claimed is—

1. As an article of manufacture, a group of shingles in proper alignment and properly spaced in combination with one or more 95 thin flexible metal strips secured along the backs thereof by metal connections.

2. A securing strip for the purpose described consisting of a thin metal band having evenly spaced folding flaps along one longitudinal edge and pairs of lugs 100 similarly spaced stamped up from the body of the band.

3. In a shingle fastener, an elongated member adapted to be secured to a roof and having a pair of spaced normally upstanding ears, said ears adapted to be bent downwardly over the edges of a shingle over 105

lying said member for securing the said edges.

4. In a shingle fastener, an elongated member adapted to be secured to a roof and having a plurality of pairs of normally up-standing ears in series, the said ears being adapted to be bent downwardly over the

edges of shingles overlying said member for securing said edges, the said pairs being arranged so as to provide intervening spaces between the said shingles.

In testimony whereof I have hereto set my hand.

E. J. WILLIAMS.
